TIRE

Yoshi Oita, Kobe, Japan, assignor to The Dunlop Company Limited, Birmingham, England, a British corporation

Filed June 16, 1969, Ser. No. 17,720

Claims priority, application Japan Dec. 18, 1968

Term of patent 14 years

Int. Cl. D12—14

U.S. Cl. D90—20

FIG. 1

FIG. 2

FIG. 3

FIG. 4

FIG. 1 is a fragmentary plan view of the tire of my design.

FIG. 2 is a section on line 2—2 of FIG. 1.

FIG. 3 is an underneath plan view.

FIG. 4 is a side elevational view thereof, the opposite side being the same.

It is to be understood that the design as shown continues throughout the circumference of the tire.

I claim:

The ornamental design for a tire, as shown and described.
